UNITED STATES PATENT OFFICE.

MARVIN LEE CANTRELL, OF PUEBLO, COLORADO.

KIDDIE-COASTER.

1,344,023.

Specification of Letters Patent. Patented June 22, 1920.

Application filed March 28, 1919. Serial No. 285,901.

To all whom it may concern:

Be it known that I, MARVIN L. CANTRELL, a citizen of the United States, residing at Pueblo, in the county of Pueblo and State 5 of Colorado, have invented new and useful Improvements in Kiddie-Coasters, of which the following is a specification.

This invention has reference to a child's car or coaster, and has among its objects to 0 provide a wheeled toy with means whereby the seat or body board thereof may be retained at any desired elevation with respect to the running gear so that the toy may be adjusted for different sized children, the 5 construction being also such as to permit of the removal of the seat board to convert the device from a car to a coaster.

A further object of the invention is to 0 produce a wheeled toy of this character which shall be of a simple but strong construction and manufactured cheaply.

Other objects and advantages will appear as the nature of the invention is better understood, reference being had to the accompanying drawings, in which:

Figure 1 is a side elevation of a wheeled toy constructed in accordance with this invention.

Fig. 2 is a top plan view thereof.

Fig. 3 is a sectional view approximately 30 on the line 3-3 of Fig. 2 illustrating, by the dotted lines the seat board adjusted with respect to the running gear.

Fig. 4 is a view illustrating the device 35 with the seat board removed, as when the toy is employed as a coaster.

Fig. 5 is a sectional view approximately 40 on the line 5-5 of Fig. 1.

Fig. 6 is a sectional view approximately 45 on the line 6-6 of Fig. 2.

The board supporting the wheels of the toy will for the sake of convenience be hereinafter referred to as the running board, the same being indicated by the numeral 1. The running board is preferably 50 wider at its rear than at its forward end, its edges being cut away at a suitable distance from its said rear end. On the under surface of the running board 1, at the rear widened portion thereof is secured a strap 2 having angle depending ends 3. In the lower and preferably widened portions of the ends 3 is journaled an axle 4 having its end provided with wheels 5. The front of 55 the board 1 is preferably rounded, and passing through a central round opening in the

said front is a steering post 6, the latter carrying at its lower end a yoke 7 provided with an axle 8 on which is journaled the steering wheel 9. If desired, suitable anti-frictional means may be arranged between the running board and the yoke 7, and, as illustrated by the drawings the steering post 6 has secured thereon a flanged disk 10 contacting with a similar disk 11 secured to the under face of the running board 1. The steering post 6 has removably secured to its upper end a guide handle 11.

The body or seat board is indicated by the numeral 12 and is of a shape approximately 70 similar to that of the running board, but is of a less length than the said running board. The seat board 12, at the front thereof is provided with an opening 13 through which the steering post 6 passes.

Secured to the running board 1, to the rear of the steering post 6 is the straight foot portion 14 of an angularly disposed brace member 15. The upper end of the brace is straight as indicated by the numeral 80 16 and is provided with an opening through which the steering post 6 passes. This member 15 provides a brace for the steering post. The front brace for the seat board comprises 85 two members. The lower member is indicated by the numeral 17, having its lower end formed with an offset portion or foot 18 that is secured to the running board forward of the post 6. The member 17 is preferably flat and is provided, at desired spaced 90 intervals with apertures 19. The upper section of the front brace is indicated by the numeral 20 and has its upper portion provided with an angle flange 21 having an opening 22 through which the post 6 passes 95 and a second opening receiving a securing element in the nature of a screw 23. The end of the brace 20 has an offset finger 24 designed to be received in any of the apertures 19 of the plate 17. This finger may, if 100 desired, be provided with an opening through which passes a cotter pin 25 for securing the plate 20 on the plate 17.

The rear brace includes a foot portion 26 that is bolted or otherwise connected to the 105 foot board 1, such connections being indicated by the numerals 27. From the foot arises a straight plate 28 having spaced apertures 29 and an elongated slot 30 above the said apertures. The rear brace also comprises two sections, the upper section or plate being indicated by the numeral 31,

the latter having its upper end formed with an offset portion or flange 32 that is secured as at 33 to the under face of the seat board 12. The plate 31 has a headed stud 34 that 5 passes through the slot 30 in the plate 28, and in addition to this a securing element preferably in the nature of a bolt 35 that passes through an opening in the plate 31 and is designed to be received in any one of 10 the spaced openings 30 in the plate 28. The nut 35 is engaged by a bolt 36.

From the foregoing, it will be noted that the seat board may be adjusted to any desired height with respect to the running 15 board. By removing the rear brace from the foot board and by removing the handle 11 from the steering post and likewise by removing the screw 23 that connects the flange of the front members to the seat 20 board, the said seat board may be removed from the remainder of the construction, and by replacing the handle 11 the device may be employed as a coaster as illustrated in Fig. 4 of the drawings.

25 Having thus described the invention, what is claimed as new, is:—

1. In a wheeled toy for children, a running board having wheels on the rear there-

of, a steering post passing through the front end of the running board and having a 30 guide wheel thereon, a brace for the steering post on said running board, a seat board above the running board and receiving therethrough the steering post, removable and adjustable supporting means between 35 the seat board and the running board, and a removable handle for the steering post.

2. In a wheeled toy for children, a running board, wheels at the rear end thereof, a steering post passing through a guide 40 opening in the front of the running board, a guide wheel on the steering post, a supporting brace for the steering post connected to the running board, a seat board above the running board receiving through 45 the front end thereof the steering post, brace means between the seat board and the running board one of which being removably secured to the running board and the other to the seat board, each of said brace means 50 comprising a pair of lapping adjustable sections, means for securing the sections adjusted, and a removable handle for the turning post.

In testimony whereof I affix my signature. 55
MARVIN LEE CANTRELL.
